United States Patent Office

Des. 223,916

Patented June 20, 1972

223,916

BATHROOM TOILET UNIT

Myron J. Ament, Bethel Park, Pa., assignor to Wallace-Murray Corporation, Pittsburgh, Pa.

Filed Sept. 25, 1970, Ser. No. 25,199

Term of patent 14 years

Int. Cl. D23—02

U.S. Cl. D23—49

FIG. 1

FIG. 4

FIG. 5

FIG. 2

FIG. 3

FIG. 1 is a perspective view of the bathroom toilet unit embodying my new design;

FIG. 2 is a front elevational view thereof;

FIG. 3 is a side elevational view thereof;

FIG. 4 is a top plan view thereof; and

FIG. 5 is a bottom plan view thereof.

The rear of the unit is generally hollow and unornamented.

I claim:

The ornamental design of a bathroom toilet unit, as shown and described.
